CLAIM

The ornamental design for a bicolored curved ball hitch, as shown and described.

DESCRIPTION

FIG. 1 is a top perspective view of a bicolored angled ball hitch showing my new design.

FIG. 2 is a left side view showing the bicolored curved ball hitch of FIG. 1.

FIG. 3 is top view of the bicolored curved ball hitch of FIGS. 1-2.

FIG. 4 is a rear view of the bicolored curved ball hitch of FIGS. 1-3.

FIG. 5 is a right side view of the bicolored curved ball hitch of FIGS. 1-4.

FIG. 6 is a bottom view of the bicolored curved ball hitch of FIGS. 1-5.

FIG. 7 is a front view of the bicolored curved ball hitch of FIGS. 1-6; and,

FIG. 8 is the top perspective view of FIG. 1, for the purpose of showing the colors of the bicolored curved ball hitch.

The stippling of the shank portion is intended to show that the shank portion has a textured, flat appearance and the shading of the shank portion is intended to show that the shank portion is colored black. The oblique line shading of the ball portion is shiny, smooth metallic chrome.
